UNITED STATES PATENT OFFICE

111,336

DESIGN FOR A SIGNBOARD OR SIMILAR ARTICLE

Charles Frederick Smith, Larchmont, N. Y., assignor to General Outdoor Advertising Co. Inc., New York, N. Y., a corporation of New Jersey

Application July 13, 1938, Serial No. 78,437

Term of patent 14 years

To all whom it may concern:

Be it known that I, Charles Frederick Smith, a citizen of the United States and a resident of Larchmont, New York, in the county of Westchester and State of New York, have invented a new, original, and ornamental Design for a Signboard or Similar Article, of which the following is a specification, reference being had to the accompanying drawing, forming a part thereof.

I claim:

The ornamental design for a signboard or similar article, as shown.

CHARLES FREDERICK SMITH.
